[57] CLAIM

The ornamental design for a goal post structure, as
shown and described.

DESCRIPTION

FIG. 1 is a right side and front perspective view of the
goal post structure showing my new design.

FIG. 2 is a top plan view of the goal post structure
design. The bottom plan view is identical thereto.

FIG. 3 is a front elevational view of the goal post struc-
ture design. The rear elevational view is identical
thereto.

FIG. 4 is a right side elevational view of the goal post
structure. The left side elevational view is identical
thereto.
